UNITED STATES PATENT OFFICE.

CARL A. GUSTAFSON, OF MINNEAPOLIS, MINNESOTA, ASSIGNOR TO RUSSELL-GRADER MANUFACTURING COMPANY, OF MINNEAPOLIS, MINNESOTA, A CORPORATION OF MINNESOTA.

ROAD GRADER.

Application filed June 23, 1927. Serial No. 200,882.

This invention relates to new and useful improvements in road graders, generally, and more particularly to such graders comprising a main frame having a scraper blade movably mounted therebeneath, and, an object of the invention is to provide in connection with such a machine, means for taking up all play or looseness in the joints between the scraper blade and the operating mechanism therefor, thus preventing or minimizing the chattering of the blade, when engaged with a hard ground surface.

A further object of the invention is to provide a road grader, having crank shafts mounted thereon for vertically adjusting the scraper blade, which are operable by means of worm-and-gear mechanisms, and the crank-shaft supporting bearings adjacent to the worm gears, having eccentric means for relatively adjusting the gears with respect to the worms for the purpose of taking up play therebetween and, further, means are provided for taking up end play in the worms.

A further object is to provide a road grader having a crank-shaft mounted thereon for raising and lowering the scraper blade, and the crank end of the shaft being supported in a bearing having means for taking up play therein, such means comprising a semi-annular cap or collar fitted over the shaft and secured in adjusted position by means of a lock screw.

A further object is to provide a grader having a draft frame mounted therebeneath and pivotally connected at one end to the grader frame, and a circular blade-supporting frame being adjustably connected to the rear end of the auxiliary frame and adapted for rotative movement thereon to adjust the angular position of the blade with respect to the longitudinal axis of the grader, and means being associated with the auxiliary frame and the circular frame to take up play therebetween to prevent the blade from chattering when engaged with the ground surface.

The particular object of the invention, therefore, is to provide, in connection with a road grader, adjustable means for taking up play or looseness in the joints in the operating mechanism between the scraper blade and the hand-wheel, usually provided

for raising and lowering the scraper blade with respect to the ground level. 55

Other objects of the invention will appear from the following description and accompanying drawings and will be pointed out in the annexed claims.

In the accompanying drawings there has been disclosed a structure designed to carry out the various objects of the invention, but it is to be understood that the invention is not confined to the exact features shown, as various changes may be made within the 65 scope of the claims which follow.

In the accompanying drawings forming part of this specification:

Figure 1 is a view in side elevation, showing a conventional type of road grader with 70 the invention applied thereto;

Figure 2 is an enlarged detailed sectional view showing the connection between the scraper blade supporting frame and the main frame of the grader; 75

Figure 3 is an enlarged detailed sectional view on the line 3—3 of Figure 1;

Figure 4 is a detailed sectional view on the line 4—4 of Figure 5;

Figure 5 is an enlarged detailed sectional view on the line 5—5 of Figure 4, showing the means provided for taking up play in the bearing; 80

Figure 6 is an enlarged detailed sectional view, showing the worm-and-gear mechanism for rotating the blade-operating crank shaft; 85

Figure 7 is a detailed sectional view on the line 7—7 of Figure 6, showing the eccentric for relatively adjusting the position 90 of the worm gear with respect to the worm;

Figure 8 is a sectional plan view on the line 8—8 of Figure 6, showing the take up means between the worm supporting bearings; 95

Figure 9 is an enlarged detailed sectional view of the eccentric removed from the shaft;

Figure 10 is a detailed plan view showing the connection between the auxiliary 100 frame and the circular blade supporting frame; and

Figure 11 is a detailed sectional view on the line 11—11 of Figure 10.

In the selected embodiment of the invention here shown, for purposes of disclosure,

there is illustrated a conventional road grader, comprising the usual main frame 2 mounted upon suitable carrying wheels 3 and 4. The usual draft frame 5 is shown beneath the main frame 2 and has a pivotal connection with the forward end of the grader in the usual manner. The circular blade-supporting frame 6 is rotatably mounted upon the rear end of the draft frame 5 and has the scraper blade 7 attached thereto, as shown in Figure 1.

In the operation of a road grader, it is essential that the scraper blade 7 is retained substantially rigid with respect to the main frame 2 of the grader, when engaged with the ground surface. In other words, it is essential that all of the joints in the connections between the blade and the grader frame are substantially free from play or looseness, in order that the blade will be prevented from chattering when engaged with a hard road surface. Such elimination of blade-chattering is of utmost importance because a smooth road surface cannot be obtained with a chattering blade, and an important feature of this invention is to provide means for thus taking up all play and looseness in the connections between the scraper blade and the hand wheel 8, provided adjacent the rear end of the grader for manually controlling the vertical adjustment of the scraper blade.

The circular frame 6, as before stated, is rotatably connected with the draft frame 5, the rear end of which has a transversely disposed cross member 9 secured thereto, and to the terminals of which the lower ends of connecting rods 11 are pivotally connected, the upper ends of which are similarly connected to crank arms 12, secured to a pair of crank shafts 13 mounted in bearings 14 and 15, secured to the main frame 2. Each crank shaft 13 has a worm gear 16 secured thereto which meshes with the worm 17, having shaft extensions 18 and 19 mounted respectively in bearings 21 and 22. The hand wheels 8 are terminally secured to the shaft extensions 18 as shown in Figure 8, whereby the worms may be operated independently of each other, as is common practice.

Means are provided for taking up play between the intermeshing teeth of the worm wheel 16 and the worm 17, and consists of an eccentric bearing sleeve 23 being rotatably mounted in each bearing 15, as shown in Figure 7. Each bearing sleeve 23 has a flange 24 provided at one end thereof, in which is an arcuately formed slot 25, as shown in Figures 6 and 9. A stud 26 traverses each slot 25 and is secured to the end of the complementary bearing or hub 15. The studs are terminally threaded to receive nuts 27, which function to lock the eccentric sleeves 23 in their adjusted positions. Referring to Figures 6 and 7, it will be noted

that when the sleeve 23 is rotated in the hub 15, the crank shaft 13 will be moved towards or closer to the worm wheel 17, thus moving the teeth of the worm and gear into closer intermeshing relation with the resultant elimination of play therebetween.

The bearing 22, supporting the shaft extension 19 of the worm wheel 17, is adjustably secured to its supporting bracket 28 by means of bolts 29 and slotted apertures 31, shown in dotted lines in Figures 6 and 8. The bearings 21 and 22 are each provided with an outwardly extending lug 32 which are apertured to receive a tie bolt 33, as shown in Figure 8. By means of this tie bolt and the adjustment afforded the bearing 22, end play may be taken up between the two bearings to prevent relative axial movement of the worm 17.

The bearing brackets 14 at the forward end of the crank shafts 13 are also provided with means for taking up play therein, caused by wear and so on. Referring to Figure 5, it will be noted, that each bearing bracket 14 has a semi-annular bearing cap or sleeve 34 which cooperates with the bracket 14 to provide a bearing for the shaft. Each bracket 14 has an enlarged semi-circular opening 35 adapted to receive the bearing caps 34, as shown in Figures 3 and 5. Shims 36 are interposed between the lower bearing faces 37 and the adjacent faces of the cap 34 to accurately space the cap from the faces 37 of the bearing bracket 14. A set screw 38 is received in threaded engagement with the upper portion of each bracket 14 and terminally engages its complementary cap 34 to lock the latter in adjusted position. An oil pipe 39 is secured to each cap 34 and to the outer end of which may be secured an oil cup, whereby oil may be introduced into the bearing.

Another feature of the invention resides in the means provided for taking up play between the circular blade-supporting frame 6 and the draft frame 5. Such means is shown in detail in Figures 10 and 11. Referring more particularly to Figure 10, it will be noted that the draft bars 5 are secured to the transverse member 9 by means of brackets 41, each having an outwardly projecting tongue or flange 42 positioned beneath the inner horizontal web 43 of the circular frame 6, which it will be noted, by reference to Figure 11, is of T-shaped cross section. Each bracket 41 is further provided with an overhanging portion 44 having a square socket 45 in the under surface thereof, in which is received a clamping block 46, shown particularly in Figure 11. These clamping blocks are retained in adjusted positions by means of adjusting screws 47, and cooperate with the flanges 42 to provide guides or bearings for the circular frame 6. In practice, the adjusting screws 47 are usu-

- ally adjusted so as to permit the circular frame to be adjusted or rotated with respect to the draft bars of frame 5, and if the road surface is found to be hard and the blade 5 has a tendency to chatter, the clamping blocks 46 may be clamped against the web 43 to securely lock the circular frame to the draft frame, thus positively preventing any play therebetween.
- 10 From the foregoing, therefore, it will readily be understood that by the employment of the various play take-up devices interposed in the connections between the scraper blade and the main frame and also 15 the hand wheels 8, that all play or looseness in the joints can be taken up so that the blade, when engaged with the road surface will have, in effect, a rigid connection with the main frame 2 of the grader. The take-up means featured in this invention have 20 therefore been found very essential in the operation of road graders or road working machines, employing a ground working blade, as, by their employment, the blade 25 will be positively held against play, thus producing a smooth and uniform cut in the road surface. The combination of the various take-up means, as set forth in this invention, are therefore essential to the successful 30 operation of the road grader, as they operate with one another to obtain one result, namely, that of eliminating all looseness or slack in the connections between the scraper blade and its operating mechanism.
- 35 I claim as my invention:
1. A road grader comprising in combination, a main frame, a draft frame pivotally connected thereto, a scraper supporting frame, a guide bracket secured to the draft frame and adapted to receive and guide said scraper frame, a socket in the bracket, a block mounted in said socket, and means for moving said block into engagement with said scraper supporting frame to take up play therebetween. 40
2. A road grader comprising a main frame having a draft frame connected therewith, guide brackets secured to the rear portion of said draft frame, a scraper frame adjustably mounted in said guide brackets, a socket in each bracket, a block mounted in each socket, means for moving said blocks into engagement with said scraper frame, operating mechanism connected with said draft frame for raising and lowering said draft frame 50 and said scraper frame, and non-yieldable take-up means in the connections between said draft frame and said operating means. 45
3. A road grader including a draft frame having guide brackets secured to the rear portion thereof, a tool-supporting frame adjustably mounted in said guide brackets, a block mounted in each bracket, and means for moving said blocks into engagement with said tool-supporting frame to take up play. 60
4. A road grader including a draft frame having guide brackets secured to the rear portion thereof, a scraper frame adjustably mounted in said brackets, a block inseparably mounted in each bracket, and adjusting screws in said brackets adapted to move said blocks into engagement with said scraper frame to take up play. 65

In witness whereof, I have hereunto set my hand this 4th day of May, 1927.

CARL A. GUSTAFSON.
